UNITED STATES PATENT OFFICE.

ALFRED F. JOHNSON, OF SOMERVILLE, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed December 20, 1924. Serial No. 757,150.

This invention aims to provide improvements in separable fasteners, primarily though not exclusively for use as three-side lock fasteners.

5 In the drawings, which illustrate a preferred and a modified form of my invention:

Figure 1 is a front elevation of the preferred form of fastener;

10 Fig. 2 is an enlarged section on the line 2-2 of Fig. 1, being partly in elevation;

Fig. 3 is a rear elevation of the preferred form of socket;

15 Fig. 4 is a rear elevation of the resilient jaw-presenting member;

Fig. 5 is a vertical section through the preferred form of socket;

20 Fig. 6 is a front elevation of the modified form of socket;

Fig. 7 is a rear elevation of the modified form of resilient jaw-presenting member; and

25 Fig. 8 is a section on the line 8-8 of Fig. 6.

Referring to the drawings, I have shown a three-side lock fastener including a socket 25 which is of a simple, inexpensive and durable construction, pressed from sheet metal and presenting spring jaw means for engagement with the neck of the stud.

Referring to the preferred form of my invention as illustrated in Figs. 1 through 5, I have shown the usual stud, including a head 1, neck 2, shank 3 and attaching screw 4, secured to a support 5, which may be the body of an automobile or other like rigid support.

35 The preferred form of socket is secured to a curtain 6 of an automobile and comprises a stud-receiving or front plate 7 and an attaching or back plate 8 secured to opposite sides of the curtain 6 by a plurality of attaching prongs 9 struck up from the front plate 7. These prongs pass through the curtain 6 and then through slots in the back plate, and are thereafter clinched inwardly and downwardly against the face 45 of the back plate 8. The curtain is not squeezed tightly between the front and back plates, as is the usual practice, and the slots in the back plate are substantially large to permit free movement of the prongs relative 50 to the back plate 8 for purposes more fully hereinafter described.

The stud-receiving or front plate 7 is formed to present (Fig. 1) a continuous ring-

like member, U-shaped in crosssection with the edges thereof bent under the ring-like 55 part 10 to provide a smooth surface for contact with the curtain 6. This ring-like portion, in the socket illustrated, is yieldable laterally when the socket is engaged with or disengaged from a stud, as will hereinafter 60 appear. The front plate also presents a pair of neck-engaging jaws 11, which extend from the ring-like portion of the front plate toward the center of the front plate 7 where they form a stud-receiving aperture 12 for 65 reception of the head of the stud.

The jaws 11 cover a relatively large area adjacent the aperture in the curtain 6, so that little or no ragged edge of the curtain is exposed at the center of the front plate even 70 after the aperture has been enlarged by wear. The jaws also present rounded neck-engaging portions 13 for smooth engagement with the neck of the stud.

75 The back plate 8 presents an aperture 14 which fits relatively close to the shank of the stud at three sides thereof to prevent tipping of the socket relative to the stud in three directions and is extended at the fourth side to permit relative tipping movement between 80 the socket and the stud in a predetermined direction only.

The back plate is also provided with an extended bearing surface in the form of a lip 85 formed from metal pressed out from the back plate to form the aperture 14 therein, and this lip extends from the periphery of the aperture at the three sides thereof which closely embrace the shank of the stud.

90 Engagement of the socket with the stud is effected by pressing the socket over the head of the stud which passes through the aperture in the back plate, curtain and front plate, so that the neck-engaging jaws 11 are spread laterally with the ring-like portion 10 to permit passage of the head therebetween to permit engagement with the neck of the stud, as illustrated in Fig. 2. During engagement of the socket with the stud, the ring-like portion of the front plate contracts on a diametrical vertical line as viewed in Fig. 1, and expands on a horizontal diametrical line, or in other words the socket yields laterally as above stated thereby to enlarge the stud-receiving aperture 12 to permit passage of the 105 head of the stud therethrough. During en-

gagement of the stud with the socket, the attaching prongs 9 shift freely relative to the back plate 8 thereby to permit free expansion and contraction of the front plate without 5 interference between the prongs and the back plate. The shiftable movement of the attaching prongs 9 is not interfered with by the curtain 6 because the curtain is sufficiently flexible to permit the prongs 9 to shift laterally relative thereto.

When the socket is engaged with the stud, it is locked therewith against separation by lateral strain because the lip 15 engages three sides of the shank 3 of the stud and prevents 15 expansion of the front plate. The socket is also locked with the stud against separation by tipping action at both sides of the stud or above the stud adjacent the body of the curtain also because of the lip 15 which closely 20 embraces the shank of the stud so that it engages therewith when any outward strain is exerted upon the socket from the above-mentioned three sides thereof.

The socket may be tipped out of engagement with the stud by a slight pull on the lower or free edge of the curtain, because the elongated aperture in the back plate allows the socket to tip without the back plate engaging the shank of the stud as it does when 25 strain is exerted at the other three sides of the curtain. Thus the stud-receiving aperture 12 in the front plate is enlarged and the neck-engaging jaws 11 pass over the head of the 30 stud thereby permitting separation of the socket from the stud.

The modified form of socket, as illustrated in Figs. 6 through 8, includes a front plate 16 and a back plate 17, which are secured to the socket-carrying fabric in substantially 40 the same manner as the front and back plates of the preferred form of socket.

The only difference between the preferred form and the modified form of socket is the construction of the front plate 16. In this 45 instance, the neck-engaging jaws 18 are located toward the top of the socket and the laterally yieldable ring-like portion 19 as illustrated, extends from one jaw to the other in a ring-like manner although not surrounding the jaws as in the preferred form of my invention.

When the head of a stud is forced between the jaws 18 in this type of socket construction, the bend occurs at a point 20 at the lowermost 55 point of the ring-like portion 19 and extends upwardly toward both jaws, thus permitting the jaws to spread and permit passage therebetween of the head of the stud.

The downwardly projecting ring-like portion 19 also presents a favorable leverage to aid in disengaging the stud from the socket when a slight outward pull is exerted upon the lower edge of the socket-carrying fabric 8.

65 While I have shown and described a pre-

ferred and a modified form of my invention, it will be understood that my invention is best defined in the appended claims.

Claims:

1. A socket for a three-side lock fastener 70 including a front plate located upon that side of a socket-carrying fabric opposite the side from which the stud enters the socket, neck-engaging jaws integral with and formed from said front plate and a back plate located upon 75 the opposite side of the fabric from said front plate, said back plate presenting a stud-receiving aperture therethrough having a wall closely embracing the shank of a stud at three sides to oppose relative tipping movement 80 between the stud and socket at three sides thereof, while extended at the fourth side to permit separation of the stud and socket by relative tipping movement.

2. A socket for a three-side lock fastener 85 including a front plate and a back plate secured to opposite sides of a flexible carrying fabric, said back plate presenting an elongated stud-receiving aperture therethrough closely engaging three sides of the shank of a 90 stud while permitting relative tipping movement between the stud and back plate at the fourth side, said front plate having an integral resilient peripheral portion and a plurality of laterally yieldable neck-engaging 95 jaws integral with said resilient portion, said resilient peripheral portion being adapted to flex laterally thereby to allow passage of the head of a stud between said neck-engaging portions.

3. A socket for a three-side lock fastener including a resilient jaw member presenting a pair of jaws for engagement with a stud, a back plate presenting an elongated stud-receiving aperture, and a plurality of attaching 105 prongs presented by said resilient jaw-presenting member, said prongs passing through a socket-carrying fabric and relatively large slots in said back plate and thereafter clinched preferably inwardly and downwardly to secure said back plate and resilient jaw member to the fabric while permitting movement of said prongs relative to said back plate when the head of a stud passes between said jaws thereby causing said jaw member to flex.

4. A socket for a three-side lock fastener including a front plate having a continuous peripheral ring-like portion, a pair of jaws enclosed by said ring-like portion and integral therewith, said jaws presenting reversely bent 120 neck-engaging portions, a back plate presenting an elongated stud-receiving aperture surrounded by a wall for engagement with three sides of the shank of a stud to prevent separation of said socket and stud by a tipping 125 strain exerted at three sides thereof, and attaching means for securing said front plate and back plate to a flexible carrying fabric, said attaching means and front plate being movable relative to said back plate.

5. A socket installation for a separable fastener including a carrying medium, a stud-engaging front plate, a back plate, attaching means presented by one of said plates and engaged with the other of said plates for securing said plates to opposite sides of the carrying medium, stud-engaging jaws presented by one of said plates, a laterally yieldable portion provided by one of said plates for operatively connecting said jaws and said attaching means to provide a yieldable attachment with the carrying medium and means provided by the plate with which the prongs are engaged for permitting movement of the prongs relative thereto.
6. In a socket for a separable fastener including a one-piece stud-engaging part having a continuous laterally yieldable outer peripheral portion, a stud-engaging portion adapted to yield with said peripheral portion and attaching prongs integral with said peripheral portion for securing said stud-engaging part to a carrying fabric, said attaching prongs being adapted to shift laterally with said peripheral portion in the general plane of the carrying fabric to permit expansion and contraction of said stud-engaging portion when being engaged with or disengaged from a stud.
7. A socket for a separable fastener including a front plate presenting an integral continuous resilient portion, a plurality of stud-engaging jaws integral with said resilient portion and a back plate presenting means for preventing separation of said socket from a stud except by tipping said socket in a predetermined direction, said jaws being transversely movable relative to said back plate to permit engagement and disengagement with a stud.
8. A socket for a three-side lock fastener comprising two pressed metal parts secured to a flexible support, two or more stud-engaging jaw portions integral with one of said parts and located at and substantially surrounding a stud-receiving aperture, said jaw portions being yieldable in a plane transverse to the axis of the socket for enlargement of the stud-receiving aperture to permit engagement with and disengagement from a stud, and means providing a wall surrounding an elongated aperture in the other part for cooperation of the stud to prevent separation of the socket from a stud when a stress is exerted at three sides of the socket.
9. A three-side lock fastener comprising, in combination, a socket-engaging stud having a head, a neck and a shank portion, a cooperating socket comprising a stud-receiving plate and an attaching plate secured to opposite sides of a socket-carrying medium, a transversely yieldable outer wall portion presented by said stud-receiving plate and neck-engaging means secured to said wall and
- yieldable therewith for engagement with the neck of the stud, said attaching plate presenting an aperture surrounded by a wall closely embracing the shank of the stud at three sides to prevent tipping separation of said fastener at three sides while being spaced from said shank at the fourth side to permit tipping of said socket relative to said stud at one side for separation of the fastener.
10. A fastener comprising, in combination, a stud having a head and a neck, a socket comprising two parts, the first part for location on that side of the fastener-carrying fabric from which the stud enters and the second part for location on the opposite side of the fastener-carrying fabric, said second part having a laterally distortable peripheral portion carrying integral jaw means also laterally yieldable with the distortable portion for resilient engagement with the neck of said stud and attaching prongs extending between the two parts and securing them to the fastener-carrying medium, said attaching prongs being yieldable with the laterally distortable peripheral portion so as not to interfere with the action of the socket.
11. A fastener comprising, in combination, a stud having a head and a neck, and a socket including two pieces for application to opposite sides of the socket-carrying fabric, one of said pieces presenting a distortable peripheral portion and stud-engaging means about a stud-receiving aperture therein, and securing means holding said pieces in assembled relation on the socket-carrying fabric while presenting clearances permitting resilient distortion of said peripheral portion during entrance and withdrawal of the stud.
12. A fastener comprising, in combination, a stud having a head and a neck, and a socket including two pieces for application to opposite sides of the socket-carrying fabric, one of said pieces presenting a distortable peripheral portion and stud-engaging means about a stud-receiving aperture therein, and securing means holding said pieces in assembled relation on the socket-carrying fabric while presenting clearances permitting resilient distortion of said peripheral portion during entrance and withdrawal of the stud, the other of said pieces opposing relative tipping movement between stud and socket by a separating strain exerted in at least one direction.
13. In a fastener socket a stud-engaging part having a continuous laterally yieldable outer peripheral portion presenting jaw portions for engagement with the neck of a stud and a plurality of attaching prongs extending from said peripheral portion for securing said stud-engaging part to a flexible carrying fabric, said jaw portions and said prongs being yieldable with said outer peripheral portion in the general plane of the carrying fabric to permit engagement of the socket with

a stud without interference between the prongs and the carrying fabric.

14. A separable fastener installation comprising, in combination, a stud-carrying medium, a stud member secured thereto, a socket-carrying medium, a two-piece socket comprising two plates secured to opposite sides of the socket-carrying medium, means providing a stud-receiving aperture passing through both plates and the carrying medium, and a plurality of stud-engaging jaws formed integral with and presented by one of said plates and arranged about said aperture, said jaws being located adjacent to the opposite end of the aperture from that end which the stud enters so that, when said stud and socket are engaged, the head of the stud will be located at the outer side of the socket-carrying medium and means provided by one of said plates for cooperation with the stud when engaged with the socket to lock the fastener

against separation by stresses exerted at three sides.

15. A socket installation for a separable fastener including a carrying medium, a stud-engaging front plate, a back plate, attaching means presented by one of said plates and engaged with the other of said plates for securing said plates to opposite sides of the carrying medium, one of said plates having a laterally yieldable peripheral wall portion **U**-shaped in cross-section and provided with stud-engaging means at the inner wall of the **U**, said **U**-shaped portion and said attaching means being yieldable laterally to shift the stud-engaging means laterally to permit passage of the head of a stud between the stud-engaging means.

In testimony whereof, I have signed my name to this specification.

ALFRED F. JOHNSON.
